UNITED STATES PATENT OFFICE.

WILLIAM F. LAUTENSCHLAGER, OF CINCINNATI, OHIO.

WATER HEATER.

Application filed April 22, 1922. Serial No. 556,095.

To all whom it may concern:

Be it known that I, WILLIAM F. LAUTENSCHLAGER, a citizen of the United States, and residing at Cincinnati, in the county of 5 Hamilton and State of Ohio, have invented a new and useful Improvement in Water Heaters, of which the following specification is a full disclosure.

This invention relates to water heaters 10 designed particularly for use in hot-water heating systems wherein it is desirable to promote a rapid and constant circulation of water, and to utilize to the greatest possible extent the thermal effects of the fuel.

15 The general objects of the invention are to provide an efficient heating apparatus of simple construction and low cost of manufacture, which may be constructed at small cost, and in which standard fittings may be 20 principally employed.

Another object of the invention is the provision of a heater composed of structural units attachable to a common chamber surrounding the intake pipe leading to the 25 chamber, each unit providing concentrically related intercommunicating passages, in turn communicating with the chamber, at different levels therewithin, heat being applied at the lower end of each unit.

30 Another object of the invention is the provision of a reverberatory chamber between the drum of the heater and a hollow baffle placed thereabove for the purpose of heating the water in a branch pipe line of one of the 35 heater outlets to a relatively high degree of temperature and ejecting the more highly heated water into the said outlet at a substantial distance from the intake end of said branch line, to accelerate the circulation in 40 said outlet.

Other objects and certain advantages will appear in the description of the drawings, and in said drawings:

Figure 1 is a vertical central section 45 through the heater, the central portion of the same being broken away to permit the enlarged disclosure of remaining portions and heater connections.

Figure 2 is a sectional elevation illustrating the disposition of the heater units about the intake pipe.

Figure 3 is a section on line 3, 3, of Figure 1, viewed in the direction of the arrow.

Figure 4 is a section on line 4, 4, of Figure 1. 55

Figure 5 is a detail section on line 5, 5, of Figure 1.

The heater comprises an inverted frustum conical drum reservoir or manifold 1, hereinafter designated the drum, having formed centrally of its top an inwardly directed projection 2 of inverted frustum conical configuration, defining at the top of the drum an annular portion or pocket 3, said projection being of less height than the 60 height of the drum. Outlet pipes 4, 5, lead vertically from the pocket 3 at the top of the drum, to suitable radiators, not shown. Centrally of the bottom of the drum and in vertical alignment with and below the 65 projection 2 is disposed an intake or "return" pipe 6, provided at its lowermost portion with a suitable drain cock 7.

70 My improved heater units or elements, generally designated at 10, are arranged concentrically about the intake pipe 6, and are vertically disposed relatively thereto. Any 75 number of such units may be used but the number and relative arrangement herein shown has been found to give the most efficient results. In constructing the heater, the units, previously assembled, are secured in the bottom wall of the drum, all in vertical parallel relation with the intake pipe. The 80 construction of all units or elements is similar, and the description will therefore be directed to a single unit. The unit comprises an outer tube 11 exteriorly threaded at each end, one end, the lower, being closed by a threaded cap 12, having a removable drain 85 plug 13 in its bottom. The opposite threaded end of the tube is engageable with corresponding threads of one of the series of concentrically disposed openings in the lower horizontal wall of the drum. 90

95 The upper end of the tube 11 is provided with a tapered counterbore 14, forming a seat within which is driven or otherwise force-fitted the lower open end of a tubular member 15 designed to lie within the drum and to extend upwardly therein, as shown, to communicate with the pocket 3 a short distance below the top of the drum.

100 The member 15 is provided with a diametric cross-passage 16 in the form of a tube traversing the walls of the member 15 and

having a sealing fit therein. The cross-passage lies near the lower end of the member 15 and adjacent its point of union with the conduit or tube 11, in the bottom portion 5 of the drum, as shown. The outside diameter of the tube forming the cross-passage is less than the inner diameter of the tube 15, providing circulating passages 17, at each side, as best shown in Figure 4. Connected 10 with the cross-passage and forming with the cross tube a T is a vertically disposed depending short section of pipe providing a threaded socket in its lower end within which is engaged the corresponding threads of an 15 inner tube or conduit 18, of less diameter than the tube 11, open at its lower end and in communication with the tube 11 near the closed end of said tube 11. This construction provides a central tubular down-passage, 20 and an annular up-passage between the outer surface of said tube 18 and the inner wall of the tube or pipe 11. A spacing spider 19 is provided near the lower end of the tube 18 to center the tube. A relatively 25 thin annular column of water will thus be exposed to the reverberated heat from the fire-brick lining, hereinafter described.

The units may be constructed of standard 30 fittings and quickly and easily assembled to form heater elements, any number of which elements in turn may be connected with the drum to form a heater.

While only two outlets are shown at the 35 top of the drum it will be understood that any number may be provided. The outlet pipe 4 leads upwardly, laterally, and then vertically as shown, the elbow 20 being provided with a reduced extension 21 connected 40 through a suitable elbow and nipples with the lower or inlet portion of a hollow disk-like baffle 22 arranged horizontally above the drum, said baffle being of equal diameter with said drum. An outlet 23 45 leads centrally from the top of baffle and is connected by suitable elbows and pipes with a valve 24, which in turn is suitably connected through the elbow 25 with the horizontal pipe 26, at which point a more highly 50 heated stream of water is injected, thus increasing the circulation in the outlet pipe. The temperature in the baffle may be controlled by adjusting the valve 24 to constrict or enlarge the passageway. Suitable 55 thermometers 27, 28, are provided for determining the temperatures in the respective pipes.

The heater is supported by means of a 60 plate 30, comprising half sections clamped together about the intake pipe, said sections 65 together providing a central annular hub 31 and ears 32 through which are engaged headed clamping screws by means of which the said sections are clamped to and about the said pipe. The plate 30 is further pro-

vided with openings 33 through which burner tubes 34 are introduced, one for each unit 15, the upper end of each burner tube being disposed directly below the closed end of its respective unit so that the heat is 70 directed primarily thereagainst. Suitable supporting legs 35 are socketed in the bottom of the section plate 30. A peripheral flange 36 is provided on the upper side of the plates against which is disposed a cylindrical metal casing 38 extending upwardly to a point below the baffle, and surrounding all the elements of the heater. A dome-shaped cap piece 39 is fitted over the top of the casing, closes the baffle and provides an 75 opening at its upper end which may be connected with a suitable pipe, not shown, leading to the chimney, for disposing of the spent products of combustion. Adjacent the inner side of the casing and extending upwardly to a point immediately below the drum is a refractory lining 40 composed of fire-brick, and the outer surface of the casing 38 is covered with sheet asbestos which extends upwardly and overlaps the dome-shaped cover. Means is thus provided for preventing radiation and for directing the heat upwardly about the dome, between the dome and the baffle, whereby the thermal effects are more thoroughly utilized. 80

The action of the heater is as follows:

The heat, directed by individual burners directly against the bottom and by reverberation against the sides of each unit, causes a rapid upward circulation of the attenuated annular water column within each unit, as a result of which highly heated water is delivered within the pocketed portion 3 at the top of the drum and thence into the main outlet pipes, a portion of the water in one of said main outlet pipes passing 100 into the branch outlet or line and through the baffle therein, in which baffle the water is more highly heated, the water being subsequently ejected horizontally into the main 105 outlet pipe at a substantial distance from the intake of said branch line. This operation increases the velocity of circulation in the said main outlet pipe. The water from the return or intake pipe passes centrally between the units and is delivered to the drum centrally at the lower portion thereof in pre-heated condition. The intake water being directed toward the projection 2 is prevented in large degree from passing upwardly and is deflected and drawn laterally into the cross-passages of the heating units and thence downwardly within the tube 18 to the bottom of tube or conduit 11 and then upwardly as above described. An adjustment of the valve 24 which procures a difference in temperatures between the main and branch outlets of approximately 50° has been found most efficient, although any 110 degree of constriction or enlargement of the 115

branch passageway above the baffle may be obtained by valve adjustment, for changing the temperature ratio.

Having described my invention, I claim:

5. 1. A drum, having an inwardly directed centrally disposed hollow projection defining an annular pocket at the upper portion of said drum, outlet pipes leading from said pocket, an inlet pipe leading to the bottom 10 of said drum centrally thereof and below said projection, a plurality of circulation units detachably secured to and in communication with the interior of said drum and surrounding said intake pipe, each unit 15 providing concentric down and up-passages communicating respectively with the lower, and pocketed portions of said drum, a hollow baffle element disposed above said drum, said baffle having an intake and an outlet 20 pipe connected with an outlet pipe of said drum, respectively at points adjacent and a substantial distance therefrom, said baffle and drum relatively disposed to form a space therebetween, means for heating said 25 units, and means surrounding said units, drum and baffle, for confining heat and directing the same against the surfaces thereof.
2. A drum, having an interior annular 30 pocket at its upper portion and an unpocketed lower portion, outlet pipes leading from said pocket, an inlet pipe leading to said unpocketed portion of said drum centrally thereof, a plurality of circulation 35 units detachably secured to and in communication with the interior of said drum and surrounding said intake pipe, each unit providing concentrically disposed communicating down and up-passages, communicating respectively with the unpocketed and pocketed portions of said drum, a hollow baffle element disposed above said drum, said baffle having intake and outlet pipes 40 connected with an outlet pipe of said drum, the intake connected adjacent said drum and the outlet connected at a substantial distance therefrom, said baffle and drum relatively disposed to form a space therebetween, means for heating said units, and 45 means surrounding said units, drum and baffle, for confining heat and directing the same against the surfaces thereof.
3. In a device of the class described, a 50 hollow drum having a central inwardly and downwardly direction projection defining in the upper portion thereof an annular pocket, an outlet pipe leading from the upper part of the pocket, a cold water inlet pipe attached centrally of and at the lower side of the 55 drum beneath the projection, heater units attached to the bottom of the drum surrounding the cold water inlet pipe, each 60 unit having up and down passages communicating adjacent the bottom, said up passage opening within the annular pocket, and the down passage opening outside of 65 said annular pocket, means for applying heat against the lower end faces of the units, and means forming a heat chamber surrounding the units, drum and intake pipe 70 for confining and directing the heat against the surfaces thereof.
4. In a device of the class described, a hollow cylindrical drum having a central inwardly and downwardly directed substantially cylindrical hollow projection, of less height than the drum defining in the upper portion thereof an annular chamber, an outlet pipe leading from the upper side of the 75 drum and chamber, a cold water inlet pipe dependently attached centrally of and at the lower side of the drum beneath the depending projection, adapted to discharge against the projection, a plurality of heater units dependingly attached to the bottom of the drum surrounding the cold water inlet pipe, each having up and down passages communicating at the bottom and at their upper ends with the drum respectively within the 80 annular chamber adjacent the top thereof, and adjacent the bottom of the drum, means for applying heat against the lower end faces of the units, and means surrounding the units, intake pipe and drum for confining the heat and directing the same 85 against the surfaces thereof.
5. In a device of the class described, a hollow cylindrical drum having a central inwardly directed hollow projection of less height than the drum, defining in the upper portion thereof an annular chamber, outlet pipes leading from the upper side of the drum and top of the annular chamber, a cold water inlet pipe attached centrally of and at the lower side of the drum beneath 90 the projection and adapted to discharge thereagainst, a plurality of heater units attached in circular formation to the bottom of the drum surrounding and parallel with the cold water pipe, each unit having up and down passages communicating adjacent the bottom, said up passage opening within the annular chamber substantially central thereof adjacent the top thereof and said down 95 passage opening adjacent the lower part of the drum, means for applying heat directly against the lower end faces of the units, and a casing surrounding the drum, units and cold water intake pipe for confining heat and directing the same against their surfaces.
